WEFT PILE VELVET

Filed May 6, 1931

Inventor.

Levi Hayes

By his Attorney:- Arthur Gadd.

UNITED STATES PATENT OFFICE

LEVI HAYES, OF PENDLETON, ENGLAND, ASSIGNOR OF ONE-HALF TO RICHARD HAWORTH & COMPANY LIMITED, OF MANCHESTER, ENGLAND

WEFT-PILE VELVET

Application filed May 6, 1931, Serial No. 535,365, and in Great Britain May 29, 1930.

The invention is for an improved weft-pile velvet, and the same may be formed with cut pile of either cotton, or artificial silk for example.

5 The object of the invention is to produce or provide a fabric of this nature which, in the finished condition, is apparently free from the twill or parallel-line effect common to weft-pile velvets of ordinary kind. As is 10 understood, this parallel-line effect in an oblique direction across the face of the cloth is sometimes rendered less apparent when the weft-pile velvet concerned is of the figured or pattern type, but in those cases where the 15 fabric is to be free from pattern, the said effect is commercially and artistically undesirable.

According to my invention, a plain or non-pattern fast bound fabric may be produced 20 which is apparently of a twill-less character on the face side thereof, and thus has an appearance approaching that of a warp-pile velvet cut in the loom.

In carrying out the invention, I so weave 25 the cloth that the twill is repeatedly reversed in direction down the length of said cloth, at the face thereat, comparatively short lengths of said reversals being situated between ground picks of weft. Under 30 the conditions named, the finished velvet appears to be free from the known parallel-line effect referred to at the face of the fabric, or is in a condition which has been termed "twill-less" herein.

35 In the accompanying drawing, there is shown a form of draft for producing the fabric according to my invention.

A repeat of the same is also included, the division between the two being indicated by 40 a thick line in a vertical direction, and marked A. B.

The small circles indicate warp ends passing over pile picks of weft, and the crosses at the ground picks indicate where the warp 45 ends pass over ground picks of weft. Floats of weft between the ground picks are left plain.

The ground picks are shown combined with warps in plain or tabby weave, as is 50 understood, by way of example, the parts

marked with crosses for one line of ground picks being arranged alternately in relation to the next and nearest lines of said picks. Some of the ground picks are indicated at 1, and some of the pile picks at 2. It will be 55 seen that the latter here float over seven ends of warp in each case. These floats are afterwards cut in the hand cutting frame, or, may be, in a power cutting machine, the directions of cuts by the knife being indicated by arrow lines marked 3 below the draft. The repeatedly reversing directions of twill formed according to my invention are indicated by the alternating direction-lines shown at 4, and merely introduced for 60 explanatory reasons, which pass between pairs of warp ends passing over picks of weft marked at 5. These pairs of warp ends where so passing over picks of weft are seen to occur at alternate picks, and in a diagonal manner, the direction of the diagonal changing or reversing as indicated.

If the warp ends which are passing over successive pile picks be considered instead of those over alternate picks, it might seem 75 that they form a twill in a contrary direction, but in practice when the picks of weft are squeezed together in the process of being beaten-up in the loom, a parallel-line effect in said contrary direction is not apparent or 80 said parallel-line effect at the face of the fabric is due to warp ends passing over alternate picks of weft, and not over consecutive picks before named, and understood 85 in the weaving industry.

The pairs or groups of warp-ends forming twill referred to operate to make the fabric of a fast-bound nature.

In the example there are ten ends of warp before the repeat, and sixty-four picks to 90 the round, but the draft given is an example of how groups of warp-ends passing over pile picks of weft can be arranged in alternating manner, whether the draft be strictly adhered to, or not, so far as length of floats and number of picks between pile picks are concerned. The warp-ends passing over pile 95 picks of weft are seen to be non-adjacent, or a warp end passes under a pick of weft between a pair of warp ends passing over pile 100

picks aforesaid in the case illustrated. In addition, as already named, each pair or group of warp ends so passing over alternate pile picks is separated from another pair or group thereof by at least one pick of weft; that is to say, the warp ends which give the twill effects so passing over pile picks at non-consecutive pile picks.

In the drawing the circles 5 and lines 4 indicate the changing manner in which the twill weave produced by the warp ends binding in the weft at the face of the fabric occur according to my invention. If the twill weave were in one direction only down the piece of cloth, the parallel-line effect herein named would result as well known, but when the direction of the twill weave as shown by the varying directional lines 4, takes a zig-zag course down the face of the fabric, and the number of picks of weft between the binding picks is not great, I find that in the finished cloth so woven the parallel line effect is not apparent in either direction. The number of pile picks between binding picks in the illustration is suitable for obtaining the result named, although slight variations thereof will not affect the result desired to any practical extent.

I claim:

30 1. A fast-bound weft-pile velvet comprising floats of weft, bound in at extremes thereof by alternate warp ends passing over the weft at the face of the fabric, said alternate warp ends occurring at alternate picks of said weft, after the manner of a twill weave, then a group of binding picks, followed by further floats of weft, bound in at extremes thereof by alternate warp ends passing over the weft at the face of the fabric, said alternate warp ends occurring at alternate picks of said weft, after the manner of a twill weave, the direction of said twill weave being opposite to that of the former twill weave named, repetitions of all the foregoing down the length of the piece, whereby the directions of the twill weaves referred to take a zigzag course down said fabric, and whereby a twill-less velvet is produced after the cutting of the floats of weft and the finishing of the cloth, as herein set forth.

2. A fast bound weft pile velvet comprising floats of weft, bound in at extremes thereof by pairs of alternate warp ends passing over the weft at the face of the fabric, said pairs of alternate warp ends occurring at alternate picks of said weft, after the manner of a twill weave, then a group of binding picks, followed by further floats of weft bound in at extremes thereof by pairs of alternate warp ends passing over the weft at the face of the fabric, said pairs of alternate warp ends occurring at alternate picks of said weft, after the manner of a twill weave,

the direction of said twill weave being opposite to that of the former twill weave named, repetitions of all the foregoing down the length of the piece, whereby the directions of the twill weaves referred to take a zigzag course down said fabric, and whereby a twill-less velvet is produced after the cutting of floats of weft and the finishing of the cloth, as herein set forth.
